UNITED STATES PATENT OFFICE

2,455,799

ELECTRIC SWITCH ACTUATING
MECHANISM

Reynold A. Ohlson, Plainville, Conn., assignor to
The Trumbull Electric Manufacturing Company,
Plainville, Conn., a corporation of Connecticut

Application June 17, 1946, Serial No. 677,205

10 Claims. (Cl. 200—50)

1

This invention relates to enclosed or safety electric switches and particularly to manually operable means for actuating the contact making and braking mechanism.

The main object is to provide actuating mechanism which is adapted to be readily applied to a supporting wall, such for instance as to the cover of a switch box. Another object is to adapt the actuating mechanism to different thicknesses of walls. Other objects are to facilitate the attachment of indicating means and locking means.

Fig. 1 is a front view illustrating the invention as applied to a fragment of a switch box cover, part being broken away.

Fig. 2 is a vertical sectional view on the plane of line 2—2 of Fig. 1.

Fig. 3 is a rear view on a larger scale.

Fig. 4 is a side view and partial section of the mechanism.

Fig. 5 is an exploded sectional view of the various parts.

Fig. 6 is a rear view of the handle.

Fig. 7 is a front view of the oscillator and its hub.

As the invention relates to the actuating mechanism rather than the contact making and breaking mechanism, I have shown only a fragment 10 of the cover or other supporting wall of a housing or receptacle or switch box and only a fragment 11 of a crank shaft or other moving part of the switch mechanism.

In its preferred form the actuating mechanism has a base plate 12 secured to the box cover wall by a screw 13 which passes through an opening 14 in the box wall and seats in a screw-threaded hole 15 in a plate 16 mounted on the front of the box wall 10.

The actuating lever 17 is mounted on the stud 18 at the back of the plate 12 so that it can swing about its axis and also slide toward and from the plate 12. The outer end of lever 17 has a slot 19 through which passes the movable switch member 11. The base plate 12 has a slotted extension 20 into which the movement of the lever 17 moves the rod 11 when the circuit through the switch is closed. This locks the cover closed.

The oscillator disc 21 has a hub 22 and a headed stud 23, the latter extending into a slot 24 in the lever 17. A headed stud 25 carried by the lever 17 serves to loosely guide the lever 17 with respect to the oscillator 21. The spring 26 connects the disc 21 to a part of the base plate and tends to hold the disc 21 and lever 17 in the "Off" position of the switch.

2

When the parts are assembled, the hub 22 of the oscillator 21 extends through openings 27 in the wall 10 and plate 16 and within the sleeve 28 which is externally screw-threaded to fit the screw-threaded opening 29. Sleeve 28 has an angular flange 30 to facilitate adjustment. A washer 31 may be provided.

The handle 32 has a hub 33 with recesses 34 into which the pins 35 of the oscillator hub project. A screw 36 passes through the hub 33 and seats in the socket 37 in the hub 22. A flange 38 surrounds the flange 30 when the inner face of the hub 33 is drawn tight against the outer end of the hub 22.

15 A plate 40 is preferably provided with the "On" and "Off" indications and any other information desired. This plate is provided with an opening 41 for the passage of the sleeve 28.

The plate 16 is also provided with a flange 42 having openings 43 for the attachment of switch locking devices (not shown) for holding the handle 32 in the "On" or "Off."

To mount the device upon the cover or other wall of the box, it is necessary to cut a hole 27 in the wall for the sleeve 28 and a small hole 14 for the screw 13. The base plate 12 is then applied to the rear of the wall and the hub 22 inserted through the opening 27. The sleeve 28 is then slipped over the hub 22 and inserted through the opening 41 in the face plate 16 and opening 27 in the wall of the box and screwed into the opening 29 in the base plate until the wall 10 and the plates 40 and 16 are clamped tightly between the base plate and the flange 30 of the sleeve 28. The handle 32 is then applied and secured by the screw 36 which draws forward the hub 22 and its connected parts until the oscillator 21 abuts against the rear end of the sleeve 28. This permits the device to be applied to various thicknesses of walls. A washer 31 may be provided if desired.

From the foregoing it will be seen that the invention is applicable to various forms of enclosed switches and can be readily applied to a switch box.

Figs. 1, 2, 3, 4 and 5 show the parts assembled and with the handle and lever 17 in the "Off" position. By turning the handle from the "Off" position to the left in Fig. 1 or "On" position, the oscillator 21 is turned with it and the lever 17 is lifted so as to raise the switch rod 11 which is mounted in the switch box into the slotted abutment 20 carried by the cover so as to prevent opening the cover on which the handle 55 is mounted.

I claim:

1. Switch actuating mechanism comprising a base plate, a stud projecting from the rear thereof, an actuating lever hinged and slideable upon said stud to and from the base plate, a screw-threaded sleeve adjustably mounted in said base plate, a hub rotatable and slideable in said sleeve, an oscillator secured to said hub, an operating connection between said oscillator and said lever and an external handle detachably connected to said hub.

2. Switch actuating mechanism comprising a box wall, a stud projecting from the rear thereof, an actuating lever hinged and slideable upon said stud to and from the box wall, a screw-threaded sleeve adjustable through said wall, a hub rotatable and slideable in said sleeve, an oscillator secured to said hub, an operating connection between said oscillator and said lever and an external handle detachably connected to said hub.

3. Switch actuating mechanism including a box cover, a stud projecting inwardly from said cover, an actuating lever hinged and slideable upon said stud to and from the cover for moving a switch part, a sleeve adjustable through said cover, a hub rotatable and slideable in said sleeve, an oscillator secured to said hub, an operating connection between said oscillator and said lever, an external handle detachably connected to said hub and a slotted extension on the inside of said cover in the path of movement of said switch part for holding the parts in moved position and the cover in closed position.

4. Switch actuating mechanism comprising a box wall, a stud projecting from the rear thereof, an actuating lever hinged and slideable upon said stud to and from the box wall, a screw-threaded sleeve adjustable through said wall, a hub rotatable and slideable in said sleeve, said hub having a socket, an oscillator secured to said hub, an operating connection between said oscillator and said lever and an external handle having a hub with an opening therethrough and a fastening member extending through said opening and into the socket of said rotatable hub for clamping the parts together.

5. Switch actuating mechanism comprising a base plate having an opening, an oscillator mounted at the rear of said plate and having a hub fixed to the oscillator and insertable from the back of the base plate forwardly through said opening in said plate, a clamping sleeve slideable on said hub and having a screw threaded engagement in the opening in said plate and having a flange in front of said plate and a handle member secured to the front end of said hub.

6. Switch actuating mechanism comprising a base plate having an opening, an oscillator mounted at the rear of said plate and having a hub fixed to the oscillator and insertable from the back of the base plate forwardly through said opening in said plate, a clamping sleeve slideable on said hub and having a screw threaded engagement in the opening in said plate and having a flange in front of said plate and a handle member secured to the front end of said hub, said hub having pins interlocked with said handle and said handle having means covering the flange on said sleeve.

7. Switch actuating mechanism comprising a base plate having an opening, an oscillator

mounted at the rear of said plate and having a hub projecting forwardly through said opening in said plate, a clamping sleeve slideable on said hub and having a screw threaded engagement in the opening in said plate and having a flange in front of said plate and a handle member secured to the front end of said hub and a face plate having an opening for said sleeve and a fastening device connecting said base plate and said face plate.

8. Operating and cover interlocking mechanism for a switch with a movable arm secured within an enclosure having an openable cover, comprising an exterior operating handle pivotally mounted on said cover, switch actuating mechanism supported inside said cover, one element of said mechanism being adapted to be connected to said arm of the switch when said cover is closed, means mechanically connecting said handle to said actuating mechanism for operation of the switch arm through movement of the handle when the mechanism and arm are connected, and an interlocking projection on said cover lying partially in the path of movement of the switch arm and engaging therewith in one position of the switch arm to prevent opening of the cover.

9. Operating and cover interlocking mechanism for a switch with a movable arm secured within an enclosure having an openable cover, comprising an exterior operating handle pivotally mounted on said cover, a base plate secured inside said cover, switch actuating mechanism supported by said base plate, one element of said mechanism being adapted to be connected to said arm of the switch when said cover is closed, means mechanically connecting said handle to said actuating mechanism for operation of the switch arm through movement of the handle when the mechanism and arm are connected, and an interlocking extension on said base plate lying partially in the path of movement of the switch arm and engaging therewith in one position of the switch arm to prevent opening of the cover.

10. Switch actuating mechanism comprising a base plate and screwed into said opening, an oscillator mounted at the rear of said plate and having a hub secured thereto and insertable into base plate and screw into said opening, an oscillator mounted at the rear of said plate and having a hub secured thereto and insertable into said sleeve from the rear thereof, a handle member at the front of said base plate, a securing screw passing through said handle member and screwed into said hub and means for interlocking said handle member and said hub so that they may turn together to actuate said oscillator.
